RECIPE AND MENU CABINET

Joseph E. Hines, Kensington, Md.

Application September 7, 1939, Serial No. 293,837

2 Claims. (Cl. 40—86)

The present invention is directed to improvements in recipe and menu cabinets.

The primary object of the invention is to provide a device of this character so constructed that a number of recipes and menus can be contained in the cabinet for ready reference, and in a comparatively small space.

Another object of the invention is to provide a device of this kind constructed in such manner so that it can be suspended on a wall for convenient reference.

Another object of the invention is to produce a device of this nature, the construction being such that additional recipes may be added thereto when desired.

Still another object of the invention is to provide a cabinet for the purpose specified wherein provision is made to firmly support a stretch of the recipe bearing web to prevent distortion thereof when additional recipes are written directly upon the web or are applied thereto by pasting recipe bearing paper sheets.

Still another object of the invention is to provide a cabinet which is extremely simple in construction, durable, attractive in appearance, and one which can be manufactured at a small cost.

With these and other objects in view, this invention resides in the novel features of construction, formation, combination and arrangement of parts to be hereinafter more fully described, claimed, and illustrated in the accompanying drawing, in which;

Figure 1 is a front elevation of the device.

Figure 2 is a side elevation.

Figure 3 is a rear elevation.

Figure 4 is a sectional view on line 4—4 of Figure 3.

Figure 5 is a sectional view on line 5—5 of Figure 1.

Figure 6 is an end view, partly in section, showing the transparent panel elevated.

Figure 7 is a sectional view on line 7—7 of Figure 1.

Referring to the drawing, 1 designates a shallow frame consisting of a bottom bar 2 and end bars 3, the lower ends of which are rigidly connected to the ends of the bar 2.

The opposing faces of the bars 3 are formed with grooves 4, the purpose of which will later appear.

A transparent panel 5 is provided and has its upper edge fixed in a top bar 5', which completes the frame 1 when in its operative position. When the panel 5 is in its closed position the ends of the bar 5' rest upon the upper ends of the bars 3.

Since the side edges of the panel slide in the grooves 4 the panel can be easily raised or lowered when desired.

The inner faces of the bars 3 are formed with upper and lower diametrically opposed paired recesses 6 and 7, and in which are slidably engaged the projections 8 and 9 of the respective bearing blocks 10 and 11. Journaled in the blocks 10 is an upper roller 12 and in the lower blocks 11 a lower roller 13.

Having its terminals suitably fixed to the rollers is a web 14 and it is upon this web that the menus and recipes are printed, as indicated at 15, said web being provided with blank spaces 16, and upon which may be written or pasted additional recipes.

One of the end bars 3 is formed with slots in which the trunnions 17 of the respective rollers are engaged, said trunnions having knobs 18 thereon to facilitate rotation thereof to wind the web, as desired.

The bearing blocks 10 and 11 are retained in place by flexible strips 19 which are sprung under cleats 20 fixed to the inner faces of the bars 3, and when thus engaged the ends of said strips will yieldably engage upon the respective blocks. Since the strips 19 are flexible it is obvious that the trunnions of the rollers will have slight sliding movement due to their engagement in the bearing blocks 10 and 11. These strips 19 may be conveniently removed in order that the webs may be removed and replaced to change the web.

A backing plate 20 is provided, and forms in effect a desk over which the web travels during the winding thereof. This plate may be formed from glass or any stiff material suitable for the purpose, and has its side edges mounted in grooves 21 formed in the opposed faces of the side bars 3. The downward movement of the plate 20 is limited by the lower bearing blocks 11.

In operation the cabinet is suspended from a wall and upon rotating the knobs 18 the web will be caused to travel in a predetermined direction in order to expose the data thereon at the frame opening normally closed by the panel 5.

As shown in Figure 5, the panel 5 is elevated in order that access may be had to the stretch of web 14 exposed, and should it be desired to write a new recipe on one of the blank spaces 16 of the web the plate 20 will support the web stretch so as to prevent distortion thereof when a pencil or pen, indicated by 22 is pressed upon the web. Obviously the plate 20 will resist any pressure should it be desired to paste upon the web a strip bearing a new recipe.

What is claimed is:

1. A device of the class described comprising a frame, a pair of rollers journaled in the frame, a web having its terminals fixed to the rollers, means for rotating the rollers to wind the web from one to the other, a backing plate mounted in the frame, said backing plate being adapted to support a stretch of the web, a transparent panel slidably mounted in the frame and adapted 10 to be elevated to permit access to the stretch of web on the backing plate, said backing plate

serving to oppose pressure imparted to the web stretch thereon when the panel is elevated.

2. A device of the class described comprising a frame, bearing blocks mounted in the frame, rollers journaled in the bearing blocks, cleats carried by the side bars of the frame, resilient strips having their ends bearing upon the bearing blocks and engaged intermediate their ends with the cleats, and a reciprocating web windable from one roller to the other.

JOSEPH E. HINES.
